CLAIM

The ornamental design for a microfilm reader display panel, as shown and described.

DESCRIPTION

FIG. 1 is a front and left side perspective view of a microfilm reader display panel showing my new design;

FIG. 2 is a right end elevational view;

FIG. 3 is a top plan view;

FIG. 4 is a front elevational view; and

FIG. 5 is a rear elevational view thereof.

The bottom of the microfilm reader display panel is essentially plain and unornamented.
